DESIGN FOR A TABLECLOTH OR SIMILAR ARTICLE

Virginia Helsley, New York, N. Y.

Application January 16, 1947, Serial No. 136,167

Term of patent 3½ years

(Cl. D92—26)

To all whom it may concern:

Be it known that I, Virginia Helsley, a citizen of the United States of America, residing in New York city, county of New York and State of New York, have invented a new, original, and ornamental Design for a Tablecloth or Similar Article, of which the following is a specification, reference being had to the accompanying drawing, forming part thereof, wherein the figure is a plan view of a tablecloth, showing my new design.

I claim:

The ornamental design for a tablecloth or similar article, substantially as shown.

VIRGINIA HELSLEY.
